L. T. CANFIELD,
DRAFT ARM FOR RAILWAY CARS,
APPLICATION FILED SEPT. 16, 1915.

Patented July 11, 1916.

UNITED STATES PATENT OFFICE.

LEWIS T. CANFIELD, OF CHICAGO, ILLINOIS, ASSIGNOR TO UNION DRAFT GEAR CO., A CORPORATION OF ILLINOIS.

DRAFT-ARM FOR RAILWAY-CARS.

1,190,858.

Specification of Letters Patent. Patented July 11, 1916.

Application filed September 16, 1915. Serial No. 51,043.

To all whom it may concern:

Be it known that I, LEWIS T. CANFIELD, a citizen of the United States, and resident of Chicago, county of Cook, and State of Illinois, have invented certain new and useful Improvements in Draft-Arms for Railway-Cars, of which the following is a specification, and which are illustrated in the accompanying drawings, forming a part thereof.

The invention relates to means for strengthening the construction of railway cars and more particularly of those having wooden sills.

The increased length of railway freight trains and the increased power of locomotives, as compared with former practice, have brought about the use of larger draft appliances and require the car underframing to be of great strength. Cars heretofore constructed with wooden sills of sufficient strength to meet the conditions of service at the time of their construction are now required to be remodeled, particularly with reference to the construction of the draft plates and adjacent parts to provide for the use of larger draft appliances and for the reinforcement of the sills in line with the body bolster.

The object of the invention is accordingly to provide a draft arm comprising draft plates and a reinforcing transom adapted for application to cars having wooden sills, to provide an improved connection of the draft plates with the sills and to assist the sills in carrying the load to which they are subjected.

In the accompanying drawings, Figure 1 is a plan view showing details of a car underframing with a form of the improved draft arm applied thereto, the center sills and the end sill being omitted; Fig. 2 is a longitudinal sectional view taken on the plane indicated by the line 2-2 on Fig. 1, but showing the end sill and a detail of the corresponding center sill, partly broken away, and with the body bolster indicated in dotted lines; and Figs. 3 and 4 are transverse sectional views taken on the lines 3-3 and 4-4 of Fig. 1, but showing the center sills in both figures.

The center sills of a railway freight car are indicated at 10 and 11, one of the end sills at 12, and the deadwood at 13 and

body bolster at 14. A pair of sub-sills are 55 shown at 15, 16, these sub-sills extending only from the body bolster 14, inwardly. The deadwood 13 is preferably reinforced by an angle plate 17. This angle plate is applied to the bottom and rear faces of the 60 deadwood 13, whereby its upstanding flange extends in front of the end sill 12.

The improved construction provides a pair of draft plates 18, 19 of channel section and of large size. Each of these draft 65 plates extends from a point beneath the deadwood 13, under one of the center sills 10, 11, to the body bolster 14. Each draft plate 18, 19 has its upper flange 35 removed at its forward end to receive the deadwood 70 13, and the web 20 of each draft plate is firmly secured against the angle plate 17, as by a bracket 21. The usual front and rear draft lugs 22, 23, are provided at each side and the web 20 of each draft plate may 75 be apertured, at 41, between the corresponding draft lugs to receive the spring bolt (not shown) of a well known type of friction draft gear. A wide bearing for the rear end of each draft plate 18, 19, against 80 the body bolster 14 is provided by the use of brackets 24, 25. One of these brackets is firmly secured against the web 20 of each of the draft plates and abuts against the adjacent side of the bolster.

85 The reinforcing transom is generally designated 26. It comprises a substantially flat plate or web 27 of sufficient size to extend beneath both of the center sills 10, 11 and over and beyond the bolster 14, with an 90 upstanding flange 28, 29, at each side. Each of the flanges 28, 29, engages one of the center sills 10, 11, upon the outside and is firmly secured thereto by bolts, as 30. The intermediate portion of the plate or web 95 27, in line with the bolster 14, is upwardly offset as indicated at 31. A space or pocket 32 is thus provided below the upwardly offset portion 31 of the plate 27, and beneath the adjacent ends of the two sub-sills 15 and 16, and draft plates 18, 19. This pocket serves for the reception of the bolster 14 and the margins of the upwardly offset portion of the plate 27 provides shoulders 42, 43 in the plate for engagement with front 100 and rear edges of the bolster. If desired, the depth of the shoulder 43 may be increased and the plate 27 stiffened by rivet-

ing a supplemental plate 33 against the under side of the plate 27 immediately in rear of the bolster.

The draft plates 18, 19 are each firmly secured to the transom 26, both by rivets 34 which are passed through the floor plate 27 of the transom and through the upper flange 35 of the draft plate and by an angle bracket 36, one of which is secured 10 against the web 20 of each draft plate 18, 19, upon the inside and against the under side of the adjacent part of the floor plate 27 of the transom.

The usual vertical bolts 37 extend through 15 each of the sub-sills 15, 16 and corresponding center sill 10, 11, those shown being located in front of the inner end of the transom 26, whereby they pass through apertures 38 in the floor plate 27 of the transom, 20 as most clearly shown in Fig. 1. Similarly, some of the bolts, as 39, employed for securing the draft plates 18, 19 against the under side of the center sills 10, 11, also pass through apertures 40 in the floor plate 25 27 of the transom. The construction accordingly provides for the rigid connection of the transom 26 with the angle plate 17 in front of the end sill 12, through the draft plates 18, 19 and the center sills 10 and 11 30 are amply reinforced to withstand the strains imparted thereto. The transom 26 by reason of its upstanding flanges 28, 29, and floor plate 27, serves to hold the center sills 10, 11, both against lateral spreading 35 and against vertical deflection in line with the bolster. The upstanding flanges 28, 29, not only hold the sills 10, 11 against lateral spreading but their presence gives the transom great stiffness against vertical bending. 40 Furthermore, the construction is one which may be readily applied to cars already constructed and when so applied serves to provide such cars with the necessary strength for use under the present conditions of rail- 45 way freight service.

I claim as my invention,—

1. In combination a pair of draft plates,

each adapted to extend beneath one of the center sills of a car, a transom plate extending over and rigidly connecting the two draft plates and a flange extending upwardly from the transom plate at each side for engaging the outside face of the corresponding center sill.

2. In combination, a pair of draft plates, 55 each adapted to extend beneath one of the center sills of a car with its rear end abutting against the body bolster, a transom plate rigidly connecting the two draft plates and extending rearwardly therefrom over 60 the body bolster, and an upstanding flange extending continuously along each side of the transom plate for engaging the outside face of the corresponding center sill from a point in front to a point in rear of the 65 body bolster.

3. In combination, a pair of draft plates, each adapted to extend beneath one of the center sills of a car from the end sill of the car to a point adjacent the body bolster, a tie plate connecting the two draft plates at their forward ends, said tie plate having a portion extending upwardly in front of the end sill of the car, a transom plate rigidly connecting the two draft plates 75 adjacent their rear ends and extending rearwardly therefrom over the bolster, and an upstanding flange extending continuously along each side of the transom plate for engaging the outside face of the corresponding 80 center sill.

4. In combination, a pair of draft plates, and a transom plate connecting the draft plates and extending rearwardly therefrom to project over the body bolster of a car, 85 the transom plate being provided with an upstanding flange at each side forming a trough for receiving the two center sills of the car with each of the said flanges engaging the outside face of one of the sills 90 to prevent lateral spreading of the sills over the bolster.

LEWIS T. CANFIELD.
